UNITED STATES PATENT OFFICE.

CLAUDE C. LAKE, OF CHICAGO, ILLINOIS, ASSIGNOR TO NIC KRUMP, OF CHICAGO, ILLINOIS.

OVERHEAD SWITCH.

1,404,177.

Specification of Letters Patent. Patented Jan. 17, 1922.

Application filed July 25, 1921. Serial No. 427,358.

To all whom it may concern:

Be it known that I, CLAUDE C. LAKE, a citizen of the United States, and a resident of Chicago, in the county of Cook and State 5 of Illinois, have invented certain new and useful Improvements in Overhead Switches, of which the following, reference being had to the drawings accompanying and forming a part hereof, is a full and complete specification.

This invention relates to switches which are installed in over-head track systems.

Among the objects of this invention is to obtain an over-head switch which comprises 15 few parts, which is easily installed, which is durable and not liable to get out of order or break, and which is well adapted to support heavy loads. Additional objects are to obtain an over-head switch which requires no 20 base or frame for hangers, either prior or subsequent to the switch being installed.

In the drawings referred to Fig. 1 is a top plan view of a switch embodying the invention; Fig. 2 is a side elevation; and 25 Fig. 3 an end elevation of said switch.

A reference character applied to designate a given part indicates said part throughout the several figures of the drawing, wherever the same appears.

30 A represents a casting having hangers B, B, B, integral therewith and depending therefrom. a, a, a, a, represent apertures through which bolts are extended to secure said casting in position. C, C, C, represent 35 abutments which are integral with casting A, and D, Fig. 2, represents a safety member pivoted to one of said abutments. Similar safety members are pivotally mounted on each of the abutments C, C, C, and d,

40 Fig. 2, represents a bolt on which safety member D is pivoted. d' represents an abutment on member D. E represents a longitudinally movable bolt member, which is mounted in aperture e in hangers B, B, B, 45 so that one end thereof abuts against abutment d', and the other end is positioned so as to be engaged by cam F on hanger G, at the free end of the switch, as said hanger is moved to and fro in the operation of the 50 switch. Hanger G is provided with base g, at the upper end thereof, and said base rides on the arc-shaped track or table H, which is integral with casting A. h, h, h, represent recesses in table H, and I represents a longi-

tudinally movable bolt which is mounted in 55 casting or base g, and yieldingly maintained in an advanced position by spring J, in engagement with a recess h, when hanger G is in position to align rails K, K, with rails X, X, of a given track. L, (Fig. 1), 60 represents a plate which is rigidly secured on bolt I, and l, l, respectively represent flexible connections which are attached, at one end, to plate L, and by means of which said bolt is retracted from the recess h with 65 which it is engaged, against the resiliency of spring J. l', l'', represent pulleys over which the connections l, l, are mounted, so that the free ends of said connections are perpendicular. When said free ends, or 70 either of them, are pulled downward the bolt I is, at first, retracted from its recess h, and by continued downward movement of one of said free ends the free end of the switch, (including hanger G), is moved to 75 the right or to the left, as viewed in Fig. 1, as desired, along the track or table H, (base g resting on said table). The free ends of rails K, K, are thus brought into alignment with the desired ones of the rails 80 X, X, adjacent to said rails K, K. When hanger G is moved, as last above recited, the cam F is brought into engagement with one end of the bolts E, E, to move said bolt longitudinally against abutment d' of member D, 85 and thereby turn said member D on its pivot d, raising the free end of said member out of the path of a car on said tracks, and of the car about to travel over the switch. M represents a casting which is provided 90 with apertures m, m, through which bolts are designed to be extended to secure the casting in place in the over-head track system. N, N, are hangers which are integral with casting M, and n represents a tie which is integral with hangers N, N, (Fig. 2), to join said hangers and increase the rigidity thereof. O, O', represent rail supporting plates, which are secured to the lower ends 95 of hangers B, B, B, G, and N, N, respectively, by bolts P, P, P', and p. Q represents a casting to which the pivoted ends of switch rails K, K, are secured; and said casting is secured pivotally on pivot bolt p. R represents a plate which is secured at its 100 ends to castings A and M by screws r, r. Plate R corresponds in length to rails K, K, to hold hangers B, B, B, G, and N, N, in

proper relative position while the switch is being installed, with the free ends of said rails K, K, adjacent to rails X, X.

To operate the switch the perpendicular ends of connections l, l, or one thereof, is pulled down to retract bolt I from recess h, and the proper one of said ends is then pulled further downward to move the casting g and hanger G the required distance in the direction desired, to bring rails K, K, into alignment with the desired ones of the rails X, X.

I claim:

1. In an over-head switch, a casting having a plurality of hangers integral therewith and depending therefrom, and provided with an arc-shaped table, in combination with a switch-rail supporting hanger provided with a base arranged to travel on said table, switch rails, means to support one end of said rails on said supporting hanger, and means to pivotally support the other end of said switch rails.

2. In an over-head switch, a casting having a plurality of hangers integral therewith and depending therefrom, and provided with an arc-shaped table having recesses thereon in spaced relation, in combination with a switch-rail supporting hanger provided with a base arranged to travel on said table, switch rails, a rail plate, bolts arranged to secure said plate to said supporting member, an additional casting provided with hangers integral therewith and depending therefrom, a rail plate pivotally secured to one of said last named hangers, and means to secure said switch rails to said last named plate, longitudinally movable bolts in said first named switch supporting hanger, means to yieldingly hold said bolts in engagement with said recesses, and means to retract said bolts from said recesses.

3. In an over-head switch, a casting having a plurality of hangers integral therewith and depending therefrom, and provided with an arc-shaped table, and an additional casting having a plurality of hangers

integral with and depending therefrom, in combination with a switch-rail supporting hanger provided with a base arranged to travel on said table, switch rails, rail plates, means to secure said plates to said supporting hanger and to one of the hangers on said additional casting, respectively, additional rail plates, and means to secure said additional plates to said first named hangers and to the remaining hanger of said additional casting.

4. In an over-head switch, a casting having a plurality of hangers integral therewith and depending therefrom, and provided with an arc-shaped table, rail plates, bolts arranged to secure said plates to the lower ends of said hangers, an additional casting having a plurality of hangers integral therewith and depending therefrom, additional rail plates, one thereof pivotally secured to one of said last named hangers and one secured to the other of said last named hangers, in combination with a rail supporting hanger provided with a base arranged to travel on said circular table, a rail supporting plate secured to the lower end of said supporting hanger, and switch rails, one end of said rails secured to said last named plate and the other end secured to said pivotally mounted plate, and means to move said rail supporting member on said track.

5. In an over-head switch, a casting having a plurality of hangers integral therewith and depending therefrom, and provided with an arc-shaped table, an additional casting having a plurality of hangers depending therefrom, a plate attached at its ends to said casting, and a switch supporting hanger provided with a base arranged to travel on said table, in combination with rail supporting plates and bolts arranged to secure said plates to the lower ends of said hangers, and rails mounted on said plates.

CLAUDE C. LAKE.

In the presence of—

CHARLES TURNER BROWN,
NIC KRUMP.
